MAURICE J. BEENEY AND ERNEST W. BEENEY, OF NEWARK, OHIO, ASSIGNEES TO
H. F. WENDELL, OF LEIPSIC, OHIO.

CLOTHES-WASHER.

1,093,101.

Specification of Letters Patent. Patented Apr. 14, 1914.

Application filed April 8, 1913. Serial No. 759,815.

To all whom it may concern:

Be it known that we, MAURICE J. BEENEY and ERNEST W. BEENEY, citizens of the United States, residing at Newark, in the county of Licking and State of Ohio, have invented certain new and useful Improvements in Clothes-Washers, of which the following is a specification.

This invention relates to laundry devices 10 of the class wherein the cleansing operation is produced by the reciprocation of a hollow conical member having a novel arrangement of the interior parts, and whereby an alternating suction and compression is produced 15 by moving the device vertically in contact with the clothes immersed in a cleansing liquid, and has for one of its objects to simplify and improve the construction and increase the efficiency and utility of devices of 20 this character.

With these and other objects in view the invention consists in certain novel features of construction as hereinafter shown and described and then specifically pointed out in 25 the claim, and in the drawings illustrative of the preferred embodiment of the invention, Figure 1 is a sectional elevation of the improved device. Fig. 2 is a bottom plan view. Fig. 3 is a detail in section on the 30 line 3—3 of Fig. 1.

Corresponding and like parts are referred to in the following description and indicated in all the views of the drawings by the same reference characters.

35 The body of the improved device is constructed of sheet metal of any suitable quality, such as copper, aluminum, tin, or the like, and comprises a conical shell 10 having an interior socket 11 to receive an operating 40 handle 12. The socket 11 extends only part way through the conical shell 10, and at the lower end of the socket the shell is provided with a transverse diaphragm 15, preferably slightly curved downwardly, as shown, and 45 provided with a plurality of apertures 16, and forming an upper conical internal chamber 17. Depending from the diaphragm 15 is another conical member 18 which forms an inner downwardly opening conical chamber 19. Depending from the diaphragm 15 is still another and inverted conical member 20 which surrounds the conical member 18 and is united thereto at the lower end at 50 21 and forms an intermediate closed conical 55 chamber 22. The conical member 18 is pro-

vided with a plurality of apertures 23, while the conical member 20 is provided with a plurality of similar apertures 24. The conical member 20 forms an outer annular chamber 25, and the apertures 23—24 provide communication respectively between the chambers 19 and 25 and 22, while as before stated the apertures 16 provide communication between the chambers 22 and 17. Formed in the shell 10 near its upper end are a plurality of transverse openings 26. The socket 11 extends for a distance above the upper line of the shell 10, and connected to this socket and likewise connected to the shell 10 are a plurality of deflectors or hoods 27, one extending over each of the apertures 26.

Any required number of the apertures 16, 23 and 24 may be employed, but generally three will be sufficient as shown. Any required number of the apertures 26 and their respective hoods 27 may likewise be employed, but generally three will be sufficient as shown.

The shell 10 may be of any required size, 80 but for ordinary use the shell is about 8 inches in diameter at its lower end and about 7 inches long, but these dimensions may be varied as required, and it is not desired therefore to limit the invention to any 85 particular size or to any particular proportion.

With a device thus constructed, the operation is as follows: The garments to be cleansed are deposited in a suitable receptacle, such as a wash tub, and quantity of water, preferably soft, and supplied with the requisite soap or like compound, is heated to the boiling point and poured upon the garments in the tub but with not sufficient 90 water to cause the garments to float in the water. The improved implement is then disposed upon the garments in the tub and alternately moved downwardly and drawn upwardly by the handle 12 and also moved laterally from place to place in the tub to cause the cleansing action to operate upon all of the garments. As the implement is moved downwardly the air, steam and water rise into the downwardly opening chambers 95 100 and are caused to rush upwardly through the apertures 23—24 into the chamber 22 and thence through the apertures 16 into the chamber 17 and thence out through the apertures 26 and against the deflectors and 105 110

thrown downwardly thereby upon the garments. When the improved device is drawn upwardly the action is reversed, the upward movement causing a suction which draws the liquid upwardly through the garments. Thus the downward movement produces a rapid movement of the cleansing liquid downwardly through the garments, while the upward or suction movement causes an upward movement of the water through the garments, and thus entirely removes the dirt therefrom, and by repeating this action rapidly and moving the implement over laterally to bring it into contact with the entire surface of the garments, the latter are thoroughly cleansed as will be obvious. When the device is moved downwardly the water rises to a point inside of the conical chamber and above the upper edge of the holes 26 and thus confines the air which is in the space above the holes 26, and as the downward movement of the device continues the air thus confined is compressed thereby and utilized to force the cleansing liquid downwardly through the garments. The downward movement of the implement causes the water to be forced in two directions and as the device is then drawn upwardly a suction is produced which pulls the water upwardly from the bottom through the clothes, as before described. By the peculiar arrangement of the parts the splashing and throwing of the water from the tub or other receptacle is eliminated as the relatively large area of the holes permits the water to move through the device and out through the top.

In operating the device it is not necessary to draw the implement entirely out of the

water as the improved device operates as soon as the implement is raised high enough to cause the water line in the tub or other receptacle to come below the holes, which thus control the movements of the air, the air entering through the holes at the top and passing down through the upper chamber and into the concentric chambers 25-19 at the bottom. This arrangement causes the device to act quickly and materially increases the cleansing action and the utility of the action of the cleansing liquid on the garments. The members 18 and 20 are provided with drainage openings 28 at the junctures 21, as shown.

Having thus described the invention, what is claimed as new is:

A downwardly opening conical shell having transverse openings near its apex, an intermediate transverse substantially horizontal baffle member within the shell, and a hollow member depending from the baffle member and converging toward its lower end whereby an outer annular chamber and an inner chamber are formed with downwardly diverging sides, said baffle member having a plurality of openings communicating with the interior of the annular member and the annular member having a plurality of openings communicating with the chamber.

In testimony whereof we affix our signatures in presence of two witnesses.

MAURICE J. BEENEY. [L. S.]
ERNEST W. BEENEY. [L. S.]
